(57) **CLAIM**

The ornamental design for an elbow guard, as shown and described.

DESCRIPTION

FIG. 1 is a front, side perspective view of an elbow guard being worn by a baseball player;

FIG. 2 is another front, side perspective view of the elbow guard of FIG. 1 being worn by a baseball player;

FIG. 3 is a front, side perspective view of the elbow guard of FIG. 1;

FIG. 4 is a rear, side perspective view of the elbow guard of FIG. 1;

FIG. 5 is a front view of the elbow guard of FIG. 1;

FIG. 6 is a rear view of the elbow guard of FIG. 1;

FIG. 7 is a first side view of the elbow guard of FIG. 1;

FIG. 8 is a second side view of the elbow guard of FIG. 1;

FIG. 9 is a top view of the elbow guard of FIG. 1; and,

FIG. 10 is a bottom view of the elbow guard of FIG. 1.

The dashed lines shown in FIGS. 1 through 10 are included for the purpose of illustrating environmental elements only and form no part of the claimed design.

1 Claim, 7 Drawing Sheets
